UNITED STATES PATENT OFFICE.

LOUIS V. ARONSON, OF NEWARK, NEW JERSEY.

DOLL.

1,279,490.

Specification of Letters Patent. Patented Sept. 24, 1918.

Application filed February 27, 1915. Serial No. 10,915.

To all whom it may concern:

Be it known that I, LOUIS V. ARONSON, a citizen of the United States, residing in the city of Newark, in the county of Essex and State of New Jersey, have invented certain new and useful Improvements in Dolls, of which the following is a full, clear, and exact description, such as will enable others skilled in the art to which it pertains to make, construct, and use the same, reference being had to the accompanying drawings, and to numerals of reference marked thereon, forming a part of this specification.

This invention relates to certain improvements in dolls, and has relation more particularly to devices of this character known as talking and creeping dolls; and it is the object of the invention in part to provide a device of this general type, of a comparatively simple and inexpensive nature having novel and improved means, whereby the device may be caused to imitate the movements of the object which it represents, as well as to produce sounds imitative of a child, and in part to provide a device of this general character wherein the mechanism thereof is substantially invisible when the device is in operative position and normally presented to the eye.

This invention consists also in certain novel features of the construction and combinations and arrangements of the several parts of the improved doll, whereby certain important advantages are attained, and the device is rendered simpler, less expensive and otherwise better adapted and more convenient for use, all as will be hereinafter more fully set forth.

In describing my invention, reference is had to the accompanying drawings forming a part of this specification, in which like numerals of reference indicate corresponding parts in all of the views.

Figure 1 represents a plan view, partly broken away, of my improved device; and

Fig. 2 represents a side elevation of the same.

In the drawings, 1 represents a supporting frame designed to carry the operating mechanism, to the top of which is secured in any convenient or desired manner the bellows 2, as by means of pins 3 passing

through suitable apertures in the lugs 4, which are formed integral with the supporting frame 1. The supporting frame 1 is 55 preferably made from a single piece of suitable sheet material, channel-shaped in cross-section, provided with supporting pieces 5—5, located near the ends thereof. Struck up from the side walls 6—6 of the supporting frame 1 near the bottom thereof, are integral outwardly extending guides 7—7, two of which are struck up from each of the said side walls 6, each of said guides 7 provided with an elongated slot 60 8, for the reception of the extensions 9 formed on the reciprocating member 10. The reciprocating members 10 are also provided each with two elongated slots 11, for the reception of the guiding lugs 12, also 65 struck up from and which form an integral part of the side walls 6.

A centrally-arranged integral extension 13 formed on the reciprocating members 10 is provided with a slot 14, through which the 75 crank pin or stud 15 passes and which is secured to the crank 16. A lever 17, one end of which is secured to the crank pin 15, is operatively connected as at 18 to the top of the bellows 2.

The cranks 16 are secured to the ends of the operating shaft 19, and are operated by means of a pinion 20, which is fast thereon, meshing with the gear wheel 21, which is operated by spring power, as for instance, 85 the spring 22, one end of the spring being secured to the shaft 23, the other end being secured to the supporting piece 5.

The cranks 16 being set in opposite directions, give to the reciprocating members 10 90 a push and pull motion, much the same as a creeping child, one of the members 10 pushing forward while the other is pulling. This operation is continuous, one reciprocating member pushing once and then pulling, and the other member 10 pulling once and then pushing.

24 represents a gear wheel mounted upon a suitable shaft 25, forming a part of the gear train, the teeth of said wheel engaging 100 a stop 26 slidably mounted in the side walls 6 of the supporting frame, so arranged that when the stop 26 is moved in the direction indicated by the arrow, the gear train is set

in motion and the device is thereby operated.

The supporting frame 1 with its operating mechanism and attached bellows, in its operative position, is located within the body of a doll, not shown, and is invisible to the eye. The arms and legs of the doll, which are represented in dotted lines in the drawings, are secured to the extensions 9 formed on the reciprocating members 10, and when operated, the device is designed to represent a creeping doll, and to produce sounds or sayings imitative of a child.

28 represents depending flanges formed integral with the supporting frame, the inner faces of which, together with the outer faces of the side walls 6 of the supporting frame 1, form guides for the centrally-arranged extensions 13 formed on the reciprocating members 10. They, together with the elongated slots 8 in the guides 7, provide means to prevent accidental separation of the reciprocating members 10 from the guiding lugs 12.

25 The operation of the device is as follows: By means of a key engaging with the shaft 27, which projects through the body of the doll, the winding of the spring is effected. By moving the slidable stop 26, 30 one end of which projects outside the body of the doll, out of engagement with the teeth of the gear wheel 24, and in the direction indicated by the arrow in Fig. 1 of the drawings, the mechanism is set in motion and operates in the following manner. The operating shaft 19, through the cranks 16 and the crank pins or studs 15, which pass through the slots 14, cause the reciprocating members 10 to be reciprocated, at the same 35 time causing the bellows 2 to be actuated by means of the lever 17, the ends of which are operatively connected to the crank pins 15 and to the top of the bellows 2 as at 18.

40 The supporting frame 1 and the reciprocating members 10 are made from single pieces of suitable material, and are of such a nature as to lend themselves readily to manufacture from sheet metal by the use of suitable punches and dies.

50 Experience has demonstrated that the organization above described is a highly efficient one, and while the device shown and described is the preferred embodiment of my present invention, I do not wish to be limited 55 to the exact details of construction shown and described, as obvious modifications thereof will appear to those skilled in the art.

I claim:

60 1. A device of the character described, comprising a supporting frame, said supporting frame being provided with guides, reciprocating slotted sliding members having sliding engagement with the guides of said supporting frame, an operating shaft, means

operatively connected with the operating 65 shaft for reciprocating the slotted sliding members in opposite directions, and means slidably mounted in the supporting frame for controlling the movement of the operating shaft.

70 2. A device of the character described, comprising a channel-shaped supporting frame made from a single piece of suitable material, provided near the bottom thereof with integral outwardly-extending slotted 75 guides, and further provided near the top thereof, with integral outwardly and downwardly-extending channel-shaped guides, the side walls of said channel-shaped supporting frame being further provided with 80 integral guiding lugs, reciprocating members having slots near each end thereof, and provided with upper and lower extensions slidably secured to the outside of said supporting frame, said upper extensions of the 85 reciprocating members located in the guides formed in the top of the supporting frame, and the said lower extensions located in the slots formed in the guides near the bottom of the supporting frame, the guiding lugs of 90 the supporting frame engaging with the slots formed in the ends of said reciprocating members, and means for reciprocating the sliding members in opposite directions.

95 3. A device of the character described, comprising a channel-shaped supporting frame made from a single piece of suitable material, provided near the bottom thereof with integral outwardly-extending slotted 100 guides, and further provided near the top thereof, with integral outwardly and downwardly-extending channel-shaped guides, the side walls of said channel-shaped supporting frame being further provided with 105 integral guiding lugs, reciprocating members having slots near each end thereof, and provided with upper and lower extensions slidably secured to the outside of said supporting frame, said upper extensions of the reciprocating members located in the guides 110 formed in the top of the supporting frame, and the said lower extensions located in the slots formed in the guides near the bottom of the supporting frame, the guiding lugs of 115 the supporting frame engaging with the slots formed in the ends of said reciprocating members, means for reciprocating the sliding members in opposite directions, and means slidably mounted in one end of the supporting frame for controlling the movement of the said means.

120 4. A device of the character described, comprising a channel-shaped supporting frame provided with guiding lugs, said supporting frame provided with downwardly and outwardly extending integral guides, reciprocating members provided with an integral extension slidably arranged in the

said guides of said supporting frame, and further provided with elongated slots formed near each end thereof, the lugs on said supporting frame adapted to enter said slots and have sliding engagement therewith, an operating shaft, means operatively connected with said operating shaft for reciprocating the sliding members in opposite directions and slidable means mounted in the

supporting frame for controlling the movement of the operating shaft. 10

This specification signed and witnessed this 26th day of February, 1915.
